UNITED STATES PATENT OFFICE.

ARTHUR G. STEVENSON, OF ROCHESTER, NEW YORK.

ERASER HOLDER.

Application filed February 25, 1927. Serial No. 170,987.

The present invention relates to eraser holders and is designed more particularly for attaching erasers to typewriting machines and the like, having for one object to afford a practical and efficient holder for this purpose which can be readily applied to the machine to permit use of the eraser on any portion of the platen and which includes means adapted to automatically retract the eraser to normal position when released by the user.

A further object of the invention is to provide an improved holder for erasers embodying novel forms of construction affording economy in manufacture, increased length of service, convenience in operation and quick application to the machines with which it is intended for use.

To these and other ends the invention resides in certain improvements and combination of parts, all as will be hereinafter more fully described the novel features being pointed out in the claims at the end of the specification.

25 In the drawings:

Figure 1 is a front elevation illustrative of one embodiment of the invention and showing the same applied to a portion of a typewriter;

30 Figure 2 is a rear elevation;

Figure 3 is a view showing the eraser partially withdrawn from the casing;

35 Figure 4 is a side elevation illustrating the manner of applying the casing to a portion of a typewriting machine;

Figure 5 is a central section through the eraser and a stirrup or strap for supporting the same;

40 Figure 6 is a sectional elevation drawn to an enlarged scale, taken centrally through the casing and the drum therein for retracting the eraser when released by the user;

Figure 7 is a view in elevation looking 45 from the left of Figure 6 with the rear cover plate removed; and

Figure 8 is a sectional view taken on line 8a—8a of Figure 6.

Similar reference numerals throughout the several views indicate the same parts.

50 Referring to the drawings, 10 represents a portion of the frame of a typewriter to which is attached a casing 11 by means of a suitable support 12 preferably in the form of a spring clip attached as shown in Figure

55 4. An eraser 12a of a well known type has connected thereto a flexible strap or stirrup

13 attached to the outer end of a cord 14 or an equivalent flexible member connected with a reel 15 located within the casing, being journaled upon a suitable stud or spindle 16 60 projecting therein and preferably supported entirely by a plate 17 forming a closure for one end of the casing. The reel, which is preferably in the form of a drum is actuated to return the eraser to the normal position 65 shown in Figure 1 by a spring 18 which is preferably mounted within the drum having its inner end bent to form a hook-shaped portion 19 which can be readily hooked over or detached from one of a plurality of upstanding lugs 20 struck inwardly from the cover plate 17 as shown in Figures 6 to 8 inclusive. The outer end of the spring is suitably secured to the drum preferably by inserting it behind an inwardly struck portion 21 of the inner drum section 22 and bending it over the same as indicated at 23 in Figures 7 and 8. Thus, one end of the spring is rigidly fixed to the casing which in turn is fixed to the typewriting machine, 70 while the other end is fixed to the drum. Movement of the eraser by the person operating the machine to make the desired erasures from time to time will exert a pull on the cord 14 which is wound upon the drum 75 in an opposite direction from the spring, thus causing the drum to revolve upon the spindle 16 to tension or wind up the spring so that upon release of the eraser the same will be quickly and automatically returned 80 to the normal position shown in Figure 1. The winding of the spring by the pull exerted on the cord causes it to contract so that, when the cord has been withdrawn to substantially the full extent, the innermost 85 coil of the spring will be prevented from contacting with the hub 24 of the drum by the upstanding lugs 20 provided for this purpose. When the eraser is withdrawn substantially the full amount the lugs in advance of the one to which the spring is attached serve also to limit the bending action of the spring adjacent the hooked portion 19, thus avoiding the danger of breaking the spring at this point by relieving it 100 of the strains which would otherwise be produced by excessive bending of the same in the absence of any restraining means. The inwardly struck portion 21 of the drum section 22 with which the outer end 23 of the 105 spring is connected may be formed in any desired manner but is preferably in the form of

a loop, both ends of which are integrally connected with the inner section 22 of the drum. The outer section 25 of the drum is sleeved upon the inner section and has a flange 26 opposite the outwardly extending flange 27 of the inner section, the cord being wound upon the drum between said flanges as shown in Figure 6. The inner end of the cord is preferably secured to the drum by 10 extending it through a small opening in the outer section and knotting it as shown at 28. The cord is passed through an eyelet 29 secured upon the casing as shown in Figure 7, the inner surface of the eyelet being 15 rounded as indicated to avoid cutting of the cord.

The cover plate 17 is provided with a series of peripheral notches 30 adapted to receive tongues 31 on the body of the casing 20 which are bent down into engagement with the cover plate as shown at 31^a in Figure 2 whereby said plate is clamped in the desired position upon the body. The drum, the spring and the cord constitute a complete unit which may be attached to the cover plate as such before the latter is applied to the casing as described above. After inserting the spindle 16 within the hub 24 of the drum, the inner end of the spring is hooked over one of the lugs 20 as shown in Figure 7, the outer end of the spring having been previously secured to the drum as described above. The cord which extends through the eyelet 29 is attached 25 to the strap 13 preferably by extending it through the central portion thereof and tying a knot at its end. The strap is made of soft or pliable material, such as soft leather to prevent cutting of the cord. 30 The manner of attaching the spring 12 to the cover plate 17 is best shown in Figure 2. The fixed end 33 of the spring is clamped upon the cover plate by a series of tongues or lugs struck outwardly from the latter, 35 one of which is indicated at 34 which is bent down into engagement with the extreme end of the fixed portion 33, while the centrally disposed tongues 35 are bent down into engagement with the sides of said 40 spring portion, all as shown in Figure 2.

The fixed end 33 of the spring serves to cover the openings 36 in the cover plate made by striking inwardly the lugs 20 whereby dirt is prevented from entering the casing through said openings. 55

The stirrup or strap 13 is constructed as best shown in Figure 5, having a snap fastener of a well known type in which the stud portion 37 on one end of the strap projects through the eyelet 38 of the eraser into the socket member 39 on the opposite end of the strap, the eyelet serving to clamp the metal discs 40 upon the eraser in the usual manner. 60

While the holder is designed primarily for 65 erasers it is not intended to limit its use to this particular article as it is readily adaptable for holding other articles as well.

I claim as my invention:

1. An eraser holder for attachment to 70 typewriting machines comprising, a cord and a stirrup connected with the outer end of the cord comprising a flexible strip of material having a socket member on one end and a stud on the other end adapted for insertion through an opening in an eraser into the socket member to form a support for the eraser. 75

2. An eraser holder comprising a strap constructed of soft material having a snap 80 fastener with the stud portion thereof on one end of the strap and a socket portion on the other, the stud portion being arranged for insertion through an eraser into said socket portion and a cord having one end 85 connected with the strap.

3. In a typewriter attachment including a casing and a spring reel therein, the combination of an eraser having an opening therethrough, a strap of soft material having a snap fastener, the socket portion of which is secured to one end thereof and the stud to the opposite end, the stud being projected thru the opening of the eraser into the socket portion, and a cord extending 90 through a portion of the strap and secured thereto, the opposite end of the cord being connected to said spring reel. 95

ARTHUR G. STEVENSON.
